US0D1093412S

(12) **United States Design Patent** (10) **Patent No.:** **US D1,093,412 S**
(45) **Date of Patent:** **** Sep. 16, 2025**

(54) **DISPLAY SCREEN OR PORTION THEREOF
WITH A GRAPHICAL USER INTERFACE**

(71) Applicant: **IGT**, Las Vegas, NV (US)

(72) Inventor: **Christina Marie Foreman Harmon**,
Sparks, NV (US)

(73) Assignee: **IGT**, Las Vegas, NV (US)

(**) Term: **15 Years**

(21) Appl. No.: **29/942,635**

(22) Filed: **May 16, 2024**

(51) LOC (15) Cl. **14-04**

(52) U.S. Cl.

USPC **D14/485**

(58) **Field of Classification Search**

USPC **D14/485-495**

(57) **CLAIM**

The ornamental design for a display screen or portion thereof with a graphical user interface as shown and described herein.

DESCRIPTION

This application is related to the following commonly owned co-pending patent application: U.S. application Ser. No. 29/942,632, entitled "Display Screen or Portion Thereof with a Graphical User Interface".

The sole FIGURE is a front view of a display screen or portion thereof with a graphical user interface of my new design.

The dashed broken line perimeter in the drawings illustrate a display screen or portion thereof and forms no part of the claimed design. The remaining dashed broken lines in the drawings illustrate portions of the graphical user interface that form no part of the claimed design.

1 Claim, 1 Drawing Sheet
